Primary Examiner — Sandra Snapp(74) *Attorney, Agent, or Firm* — Foley Hoag LLP(57) **CLAIM**

The ornamental design for a watch, as shown and described.

DESCRIPTION

FIG. 1 is a front perspective view of a watch showing my new design;

FIG. 2 is a right perspective view thereof;

FIG. 3 is a left side elevational view thereof;

FIG. 4 is a right side elevational view thereof; and,

FIG. 5 is a top view thereof.

The features depicted by broken lines have been shown for the purpose of illustrating portions of the watch that form no part of the claimed design.
